United States Patent Office

Des. 183,158
Patented July 8, 1958

183,158

SCRAPER OR SIMILAR ARTICLE

Ruth A. Bell, Cleveland, Ohio

Application March 16, 1956, Serial No. 40,646

Term of patent 14 years

(Cl. D44—29)

Fig. 2

Fig. 3

Fig. 4

Fig. 5

Fig. 1 is a perspective view of a scraper or similar article showing my new design;

Fig. 2 is a top plan view of the scraper or similar article of Fig. 1;

Fig. 3 is a bottom plan view of the scraper or similar article of Fig. 1;

Fig. 4 is an end view of said scraper or similar article as seen from the handle thereof; and

Fig. 5 is an end view of said scraper or similar article as seen from the blade thereof.

I claim:

The ornamental design for a scraper or similar article, as shown.
